UNITED STATES PATENT OFFICE.

WILLIAM THOMPSON, OF ST. LOUIS, MISSOURI, ASSIGNOR TO THE BUCK'S STOVE AND RANGE COMPANY, OF SAME PLACE.

DESIGN FOR FIRE-BOX LINING.

SPECIFICATION forming part of Design No. 28,290, dated February 15, 1898.

Application filed January 7, 1898. Serial No. 665,986. Term of patent 14 years.

To all whom it may concern:

Be it known that I, WILLIAM THOMPSON, a citizen of the United States, residing at the city of St. Louis, State of Missouri, have invented 5 a certain new and original Design for Fire-Box Lining, of which the following is a full, clear, and exact description, such as will enable others skilled in the art to which it appertains to make and use the same, reference 10 being had to the accompanying drawings, forming part of this specification, in which—

Figure 1 is a view in perspective of my new and original design for fire-box lining as seen from the front. Fig. 2 is a side elevational 15 view of my new and original design as seen from the opposite side or from the rear, and Fig. 3 is a vertical sectional view through the central portion of the lining.

This invention relates to a new and original 20 design for fire-box linings; and it consists, generally stated, in the shape and ornamentation of the same, as will hereinafter be described.

The body portion of my newly-designed 25 lining is formed on one of its faces with a series of transversely-disposed corrugations or flutes, which terminate in a sunken recess or groove extending practically the length of

the concave face of the body portion. In the upper wall of this recess or groove are formed 30 a series of openings, as shown in Fig. 1. A rearwardly-extending flange extends from the top of the body portion, and a recessed portion extends practically the length of the rear or convex face, the lower wall of said recessed portion having a series of openings, 35 between which are raised projections, as shown in Fig. 2. The recesses in the front and rear faces are on different planes, as shown in Fig. 3, the line of openings referred 40 to practically piercing the bottom wall of the rear recess and the top wall of the front recess. In longitudinal section the lining is practically semicircular in shape.

Having thus described my new and original 45 design, what I claim is—

The design for fire-box lining substantially as herein shown and described.

In testimony whereof I hereunto affix my signature, in the presence of two witnesses, 50 this 24th day of December, 1897.

WILLIAM THOMPSON.
